(57) **CLAIM**

The ornamental design for a nozzle for dispensing viscous material, as shown and described.

DESCRIPTION

FIG. 1 is a perspective view of one embodiment of the nozzle for dispensing viscous material;

FIG. 2 is a top plan view of one embodiment of the nozzle;
FIG. 3 is a bottom plan view of one embodiment of the nozzle;

FIG. 4 is a front plan view of one embodiment of the nozzle;
FIG. 5 is a back plan view of one embodiment of the nozzle;
FIG. 6 is a left-side view of one embodiment of the nozzle;
FIG. 7 is a right-side view of one embodiment of the nozzle;
FIG. 8 is a perspective view of another embodiment of the nozzle;

FIG. 9 is a top plan view of another embodiment of the nozzle;

FIG. 10 is a bottom plan view of another embodiment of the nozzle;

FIG. 11 is a front plan view of another embodiment of the nozzle;

FIG. 12 is a back plan view of another embodiment of the nozzle;

FIG. 13 is a left-side view of another embodiment of the nozzle; and,

FIG. 14 is a right-side view of another embodiment of the nozzle.
